United States Patent Office

Des. 203,284
Patented Dec. 21, 1965

203,284

VEHICULAR TOY OR SIMILAR ARTICLE

Jarvis W. Rockwell, 3003 W. Wilson Ave., Chicago, Ill.

Filed Mar. 18, 1965, Ser. No. 84,349

Term of patent 14 years

(Cl. D34—15)

FIGURE 1 is a side elevational view of a vehicular toy or similar article showing my new design;

FIG. 2 is a top plan view thereof;

FIG. 3 is a front elevational view thereof; and

FIG. 4 is a rear elevational view thereof.

I claim:

The ornamental design for a vehicular toy or similar article, substantially as shown.
